The ornamental design for an electrical connector, as shown
and described.

DESCRIPTION

FIG. 1 is a front elevation view of an electrical connector,
showing my new design;

FIG. 2 is a top plan view thereof;

FIG. 3 is a rear elevation view thereof;

FIG. 4 is a right side elevation view thereof;

FIG. 5 is a cross-sectional view thereof, taken along the line
5—5 in FIG. 1;

FIG. 6 is a top, front and left side perspective view thereof;
and,

FIG. 7 is a bottom, rear and right side perspective view
thereof.
